CURTAIN ROD

Pierre F. Dover, Rye, N. Y., assignor to H. L. Judd
Company, Inc., New York, N. Y., a corporation
of Delaware

Application April 6, 1939, Serial No. 266,263

2 Claims. (Cl. 156—19)

My invention relates to a curtain rod.

It is an object of the invention to provide means for supporting a curtain rod in a plurality of angular positions relatively to the support.

5 A more specific object is to provide a bowed or arched curtain rod, together with means for supporting the same in a plurality of different positions to vary the effective extent of the arch or bow.

10 Other objects and various features of improvement will be hereinafter pointed out or will become apparent to those skilled in the art.

In the drawing which shows, for illustrative purposes only, a preferred form of the invention—

Fig. 1 is a view in front elevation of a window casing or other support having my improved rod support in an upper angular position;

20 Fig. 2 is an end view of the parts shown in Fig. 1 as viewed from the left;

Fig. 3 is a view similar to Fig. 2 but illustrating the rod in a different angular position;

Fig. 4 is an enlarged, fragmentary detail view in elevation of a rod end;

25 Fig. 5 is an enlarged top plan view of the rod end of Fig. 4.

The invention will be described as embodied in an extending curtain rod of the so-called flat rod type. However, the invention is of broader application and may be embodied in rods of other form.

30 The curtain rod may comprise two telescopic sections 5—6, each section being of generally channel form or C-shaped cross-section, as illustrated in Fig. 4. The mid-portion of the rod when the sections 5—6 are assembled is preferably outwardly bowed or arched, as illustrated. Each section at its outer end has an angularly bent offset portion 7, which offset portions or 35 bowed ends are adapted to be mounted on brackets for holding the rod either horizontally or tilted so as to change the elevation of the mid-portion of said rod.

The rod in the form illustrated is supported 40 on brackets of well known form, including a wall plate 8 and an offset upstanding pin 9 secured thereto. Each offset or elbow 7 is provided at one of its walls, such as the bottom wall, with a pin receiving opening 10 and is provided in the 45 other wall (in this case the top wall) with a pin receiving opening 11. The openings 10—11, as will be observed, are opposite each other and are near the extremities of the bowed ends and are also in substantially the same transverse plane 50 so that when the curtain rod is supported on the

bracket by means of the pin 9 passing through the holes 10—11 in the rod, the ends and mid-portion of the rod will be supported in a substantially horizontal plane, as will be clear from Fig. 3. The elbow or offset 7 is further provided with 5 another opening 12 in one wall, such as the top wall, and this opening 12 is spaced from the opening 11, that is, it is in a transverse plane spaced apart from the transverse plane of the openings 10—11 and somewhat further from the 10 extremity of the bowed end. When the rod is supported by the bracket pin 9 passing through the openings 10 and 12, the rod will be tilted upwardly in a different angular position, as illustrated in Fig. 2. In order to make the rod re- 15 versible I preferably provide another opening 13 in substantially the same transverse plane as the opening 12. Thus, by reversing the rod end for end, the opening 11 becomes a bottom opening and the bracket pin 9 may be engaged through 20 the opening 11 and through either of the openings 10—13 so as to support the rod in either of the two angular positions illustrated.

Thus, with the rod supported by means of the bracket pin extending through the openings 25 10—11, the mid-portion of the rod will extend outwardly or away from the window casing in a horizontal plane and one visual effect of the drapery or curtain will be produced, while with the rod supported in the tilted position as illustrated in Fig. 2, the mid-portion of the rod will 30 still be spaced away from the window casing and will also be arched upwardly so that a wholly different visual effect will be produced.

It will be noted that I have provided a curtain 35 rod with very simple means for supporting the same in a plurality of different angular positions. A particular form of rod has been illustrated and a particular form of bracket. However, it is to be observed that both rod and brackets may be 40 varied within the scope of the invention as defined in the appended claims.

I claim:

1. A hollow curtain rod having set back el- 45 bowed ends to be supported by brackets, each of said bowed ends having a pair of opposed pin receiving openings, one opening being in the upper wall and the other in the lower wall of said bowed end, each of said ends having a second pair of opposed pin receiving openings, one of 50 said second pair of openings being in the upper wall and the other opening of said second pair being in the lower wall of said end, said second pair of openings being spaced longitudinally of 55 said ends from said first pair of openings, where-

by an upturned pin on a supporting bracket may be received in either opening in one wall of said end and simultaneously in either opening in the opposed wall of said end, for the purpose described.

5 2. A hollow curtain rod having set back elbowed ends to be supported by brackets, each of said ends having a pair of opposed pin receiving openings, one of said openings being in the upper wall and the other of said pair of openings

being in the lower wall of the elbowed end, one of said walls having a second pin receiving opening offset longitudinally along said end from the first mentioned opening therein, whereby an upturned pin on the supporting bracket may be received in either of the openings in said one wall and simultaneously in the opening in the other of said walls, for the purpose described. 5
